UNITED STATES PATENT OFFICE

LORENZO AMODEO, OF NEW YORK, N. Y.

OBSERVATION BUS

Application filed December 31, 1929. Serial No. 417,696.

This invention has relation to motor driven observation or sight seeing buses of double deck construction and has for its object the construction of a vehicle of such character having greater conveniences for the accommodation of passengers than the buses now in use.

The invention relates more particularly to the construction and interior arrangement of the body of the vehicle and in the provision of novel means for seating the passengers, for facilitating their ingress and egress, and for permitting the easy and safe transition of the passengers from one compartment to another and for their ascent to and descent to and from one deck of the vehicle to another.

The invention incidentally relates to the provision of means affording access to the under part of chassis of the vehicle and for enabling the driver to open and close the several doors leading to the interior of the vehicle and between compartments.

The invention consists in the novel features of construction and combination hereinafter specifically described and claimed.

In the accompanying drawings:

Figure 1 is a top plan view of the vehicle;

Figure 2 is a side elevation;

Figure 3 is a horizontal section on the line 3—3 of Figure 2;

Figure 4 is a horizontal section on the line 4—4 of Figure 2;

Figure 5 is a vertical central section on the line 5—5 of Figure 1;

Figure 6 is a transverse section on the line 6—6 of Figure 2;

Figure 7 is a fragmentary vertical section through the lower deck portion on the line 7—7 of Figure 4;

Figure 8 is a fragmentary vertical transverse section on the line 8—8 of Figure 4; and

Figure 9 is a vertical longitudinal section of a portion of the vehicle on the line 9—9 of Figure 6.

The vehicle comprises a suitable chassis mounted on wheels 1—2 and equipped with a suitable motor of the usual character, a steering shaft and transmission and brake mechanism which need not be illustrated or described.

The body of the vehicle generally designated by the numeral 3 comprises a suitable lower floor 3' and is preferably of oval or elliptical form in horizontal section as illustrated in Figs. 1 and 3 in which the exterior wall is designated by the numeral 4 and an interior partition wall by the numeral 5.

Between these walls there is an aisle, space or corridor 6 on the lower deck of the vehicle, and on the upper deck a generally similar aisle, or passage way 6' which are in each case continuous. The inner walls or partitions define inner compartments 7, 7'. Both inner and outer spaces are provided with seats 8 and 9 conveniently arranged. A floor 10 separates the upper and lower decks.

In the middle or center portion of the floor 10 there is an opening 11, and rising from the lower floor is a winding stairway 12 leading by way of the opening 11 to the upper deck.

In both the outer and inner walls window openings 13 are provided and have window sashes with glass panes.

In the rearmost portion of the inner wall, on the upper deck, doorways 14 are arranged and lead from the inner to the outer spaces 80 or compartments.

Access is had to the vehicle by doorways 15 on either side at the front of the vehicle on the lower deck.

The door way 15 with its door 15' are intended for the entrance and exit of passengers, and the door is operable only by the driver or motor man. This door is suitably mounted for sliding movement and is attached at the top to a chain 15², which passes around suitably arranged sprocket wheels 51³, one of which is keyed upon a vertical shaft 15⁴ located near the motorman's seat 19, and provided with an operating handle 20. The chain 15² is also attached to and controls the movement of a sliding door 21 leading to the inner space or compartment of the lower deck, such door being located on the opposite side of the vehicle from the door 5'. A door way 23 in the inner wall 100

of the lower deck, provided with a hinged door 24' affords passage way to and from the inner space to the outer space adjacent to the sliding door 15, and a similar door 26 is arranged and adapted to close and open the way to the outer space on the side opposite the doorway 23.

As will be observed, the outer wall of the vehicle, extends a considerable distance below the lower floor, outside the rear wheels,

10 and to afford convenient access to the latter and the contiguous parts of the wheel installation an opening in the wall, on either side is formed, as indicated at 30, and provided with hinged gates 31 opening outwardly, opposite the rear wheels, which are located interiorly of the inner wall of the vehicle in the lower edge portion of which arcuate gaps are formed, concentric with the 15 hind wheels. Coinciding openings 32 are made in the floor of the lower deck, opposite the gates 31 and these openings have closures 33 hinged to the floor framing and opening upwardly.

20 25 When the closures 33 are raised at their free ends, access may be had to the wheels and axle ends from the interior of the vehicle and further access is facilitated by opening the gates 31 outwardly.

30 35 As illustrated in Fig. 6, the gates 31 may be made with inwardly extending ledges 34 to aid in the support of the closures 33, when the latter are closed.

40 45 The closures 33 are provided at their inner edges with wall sections 35, which, when the closures are lowered, cover the gaps in the inner wall of the vehicle. The roof of the vehicle is provided with a centrally located window 36 for observation purposes and the admission of light.

I claim:—

1. A vehicle of the type described comprising a closed body having outer and inner walls, and double floors forming lower and upper decks with outer passages, having seating capacity, and with central compartments enclosed by the inner walls, and communicating with each other by a central stairway between the upper and lower floors.

50 55 2. A vehicle as recited in claim 1, having doorways between the outer and inner compartments, and means for ingress and egress from the outside of the vehicle.

3. A vehicle of the type described comprising a closed body having outer and inner walls defining outer and inner seating compartments and bench seats in each compartment, entrance doors in each wall.

60 65 4. A vehicle of the type described comprising a closed double decked body having outer and inner walls defining outer and inner seating compartments and bench seats in each compartment, entrance doors in each wall and a central stairway between decks.

5. A vehicle of the type described com-

prising a closed body of double deck construction, an inner wall spaced from the side wall providing inner and outer seating compartments on both decks, there being communicating doorways between the compartments and a central stairway forming communication between the inner compartments of the upper and lower decks.

In testimony whereof I affix my signature.
